PULSE AMPLIFIER

William W. Moe, Stratford, Conn., assignor to
General Electric Company, a corporation of
New York

Application November 2, 1942, Serial No. 464,303

1 Claim. (Cl. 178—44)

1

My invention relates to thermionic amplifying apparatus and particularly to such apparatus which is adapted for the amplification of pulses of electrical energy which are produced at high frequencies.

It is an object of my invention to provide a pulse amplifying or transmitting apparatus including an improved arrangement for introducing a time delay between the impressing of a pulse on the input of the apparatus and the producing of a corresponding pulse at the output thereof.

It is another object of my invention to provide an improved pulse transmitting or amplifying apparatus which shall require a minimum of power for its operation.

The features of my invention which I believe to be novel are set forth with particularity in the appended claim. My invention itself, however, both as to its organization and method of operation, together with further objects and advantages thereof, may best be understood by reference to the following description taken in connection with the accompanying drawing in which Fig. 1 diagrammatically represents one form of a pulse amplifier embodying my invention and Figs. 2 through 5 are curves representing operating characteristics of my invention.

Briefly, the apparatus shown in Fig. 1 comprises two electron discharge devices connected to provide a two-stage pulse amplifier. The first electron discharge device is arranged to have the pulse or signal to be amplified impressed on its control grid and is provided with an inductance element in its anode circuit. The control electrode is provided with negative bias so that the electron discharge device is normally nonconducting and when a positive pulse of sufficient magnitude is impressed on the control grid a negative pulse appears across the inductance and energy is stored in the inductance. The anode of the first electron discharge device is coupled through a condenser to the control electrode of the second electron discharge device. The control electrode of the second electron discharge device is also biased so that the device is nonconducting and the negative pulse across the inductance has no effect. However, when the pulse impressed on the first electron discharge device is terminated, this device becomes nonconducting and the energy is released from the inductance producing a positive potential on the control electrode of the second device to render it conducting and thereby producing a pulse in the output of the apparatus. The two electron discharge devices are thus so coupled that there is

2

a delay between the time of the impressing of a pulse on the input of the apparatus and the producing of a pulse at its output. Furthermore, both electron discharge devices are normally nonconducting so that power is consumed only during the transmission of a signal.

Referring now to the drawing, in Fig. 1 I have shown a two-stage pulse amplifier or transmitting apparatus comprising a first electron discharge device 10 and a second electron discharge device 11. The device 10 is provided with a control electrode 12 which is biased negatively by some suitable means such as a battery 13 connected to the control electrode through a resistor 14. The cathode 15 of the device 10 is connected directly to ground and the anode 16 is connected through an inductance 17 to the positive side of a suitable source of direct current indicated as a battery 18. Suitable apparatus 19 for generating positive pulses of a predetermined frequency is coupled to the control electrode 12 through a condenser 20. Each of the positive pulses impressed upon the control electrode 12 renders the device 10 conducting for the duration of the pulse. When current flows in the anode circuit of the device 10, energy is stored in inductance 17 and a negative voltage pulse appears on the anode 16 as indicated at 22 in Fig. 2, the duration of the negative voltage pulse corresponding to the time during which the device 10 is conducting. The anode of the device 10 is coupled to a control electrode 23 of the device 11 through a suitable condenser 24. The control electrode 23 is connected through a resistor 25 to a suitable source of negative bias such as a battery 26, the negative bias being sufficient to render the device 11 nonconducting. It will, therefore, be apparent that the negative pulse appearing on the anode 16 is impressed on the control electrode 23 but has no effect on the device 11.

As soon as the device 10 becomes nonconducting at the end of the pulse 22, energy is released from the inductance 17 and a positive voltage pulse appears across the inductance on the plate 16 as indicated at 27 in Fig. 2. The positive pulse is impressed on the grid 23 through the condenser 24 and overcomes the bias of the grid to render the device 11 conducting and produce a pulse at the anode 28 of the device 11. The device 11 has its cathode 29 connected to ground and a suitable utilization device 30 is connected in the anode circuit of the device 11 between the anode 28 and the positive side of a source of direct current indicated as a battery 31. The duration of the pulse at the output of the apparatus de-

pends primarily upon the size of the inductance 17.

The curve of Fig. 2 has been drawn on the assumption that there was present no capacity tending to cause oscillations upon the release of energy from the inductance 17. However, there is unavoidably a certain amount of shunt capacity in the inductance which tends to cause the circuit to oscillate through several cycles such as indicated in Fig. 3 where I have shown the negative pulse 22 and the positive pulse 21 followed by a small negative pulse 33 and a small positive pulse 34 which positive pulse might cause the device 11 to become conducting. In order to prevent the occurrence of a second positive pulse, the condenser 24 may be made of a capacity such that it would be charged by grid or control electrode current flowing in the device 11 to a negative voltage as indicated at 35 in Fig. 4. The voltage applied to the control electrode 23 is the sum of the voltage of the curves of Figs. 3 and 4 as indicated in Fig. 5. It will be evident from Fig. 5 that the second cycle, indicated at 34a, does not become positive so that the device 11 conducts current only for the duration of the positive pulse 21.

During the operation of the amplifier constructed as described above current flows in the devices 10 and 11 only when a positive pulse is impressed on the control electrodes 12 and 23, respectively. At all other times the devices are nonconducting. This method of operation greatly reduces the power necessary to operation of the apparatus and makes it possible to employ electron discharge devices of smaller capacity. A time delay is provided between the pulse impressed upon the apparatus and that produced at the output of the apparatus. The circuit is therefore particularly adaptable to certain types of signaling systems requiring a time delay. Furthermore, the duration of the output pulse may be different from that of the input pulse according to the size of the inductance and the circuit constants selected.

It is readily apparent from the foregoing that I have provided a simple and effective circuit for amplifying or transmitting pulses with a minimum of power consumption. While I have shown my invention as embodied in a two-stage pulse amplifier, other modifications will readily be apparent to those skilled in the art. For example, any number of stages may be coupled together in the manner illustrated. I do not, therefore, desire my invention to be limited to the particular modification illustrated and described and I intend by the appended claim to cover all modifications within the true spirit and scope of my invention.

15 What I claim as new and desire to secure by Letters Patent of the United States is:

A pulse transmitting apparatus comprising two electron discharge devices each having a cathode and an anode and a control electrode, means for 20 biasing the control electrode of both of said devices to render said devices normally nonconducting, means for impressing a positive energy pulse on the control electrode of said first device to render said device conducting, an inductance in the 25 anode circuit of said first device for storing energy for the duration of said pulse, a resistance for connecting the control electrode of said second device to ground and a condenser for coupling the anode of said first device and the control 30 electrode of said second device whereby a pulse of positive potential is released by said inductance upon the termination of said first pulse to render said second device conducting and produce a pulse at the output of said apparatus, said inductance having shunt capacitance tending to 35 produce oscillations of energy upon the release of said stored energy and said condenser having its capacity of such value that it is charged by grid current flowing to the control electrode of said second device whereby a negative bias is produced on the control electrode of said second device to prevent a second positive pulse due to 40 said oscillations.

WILLIAM W. MOE.
